UNITED STATES PATENT OFFICE

132,903

DESIGN FOR A DUMP BODY

Fred Biszantz, Galion, Ohio, assignor to The Galion Metallic Vault Company, Galion, Ohio, a corporation of Ohio

Application December 20, 1940, Serial No. 97,490

Term of patent 7 years

To all whom it may concern:

Be it known that I, Fred Biszantz, a citizen of the United States, a resident of Galion, in the county of Crawford and State of Ohio, have invented a new, original, and ornamental Design for a Dump Body, of which the following is a specification, reference being had to the accompanying drawings, forming part thereof, wherein:

I claim:

The ornamental design for a dump body, substantially as shown.

FRED BISZANTZ.
